UNITED STATES PATENT OFFICE.

CHARLES S. BUCKLIN, OF KEYPORT, NEW JERSEY.

FRUIT AND VEGETABLE PULP MACHINE.

SPECIFICATION forming part of Letters Patent No. 426,236, dated April 22, 1890.

Application filed October 19, 1889. Serial No. 327,565. (No model.)

To all whom it may concern:

Be it known that I, CHARLES S. BUCKLIN, of Keyport, in the county of Monmouth and State of New Jersey, have invented a new and 5 Improved Fruit and Vegetable Pulp Machine, of which the following is a full, clear, and exact description.

My invention relates to a machine to facilitate the reduction to pulp of tomatoes, pumpkins, and other vegetables, and also grapes, currants, berries, and other fruits, and the separation of the pulp from the seeds, skins, &c.; and the invention consists of the construction of the machine and of its various 10 combinations and arrangements of parts, all as hereinafter described and claimed.

Reference is to be had to the accompanying drawings, forming a part of this specification, in which similar letters of reference indicate 15 corresponding parts in all the figures.

Figure 1 is a longitudinal sectional elevation of my pulp-machine on line 1 1 of Fig. 2. Fig. 2 is a transverse vertical section on line 2 2 of Fig. 1. Fig. 3 is a detailed perspective 20 view of a portion of the inner removable sieve. Fig. 4 is an enlarged perspective view of the outer sieve, and Fig. 5 is a detailed section of a part of the frame and a part of the bow which holds one end of the inner sieve.

25 The main frame of the machine comprises suitable standards or legs A A, cross-pieces B B, outer end walls C C', inner end wall D, and side walls E E. At one end of the machine is constructed the hopper F, into which the fruit or vegetables to be treated are to be fed, which find their way from said hopper to the inner sieve G through the throat F' in the end wall C'. The said inner sieve is curved or semi-cylindrical in form, and the 30

vegetables or fruits are crushed and the pulp worked through the sieve by the beater-arms H' H', which revolve with the main shaft H, which may be turned by a crank or run with belt and pulleys, as shown.

40 In addition to the inner sieve G, which is of fine mesh, and which is removable from the machine, I use an outer or lower coarse sieve I, which acts mainly as a support or reinforcement to the inner fine sieve. The two

sieves are curved or semi-cylindrical, as shown 50 clearly in Fig. 2, and are held by the end pieces C' D and side pieces E E of the main frame. The outer coarse sieve I is made fast by nails or other suitable fastenings to the longitudinal strips J' J', which fit in recesses 55 j' j', formed in the curved end ribs K. The intermediate bars J support the bottom of the outer sieve. The curved ribs K are framed into the side walls E E and fastened to the inner surfaces of the end walls C' D. The 60 bars or slats J also rest upon the intermediate plain curved ribs K', framed at their ends into the side walls E E. The curved end ribs K are channeled, as shown at k, and formed at the ends with lugs k'. These channels are 65 to receive the end bows G' of the fine inner sieve G, which fit snugly in the channels and prevent seeds, skins, and other foreign matter from passing the ends of the sieve and finding their way to the receptacle A². This 70 sieve G, besides being secured to these end bows G', is also secured to the cross-pieces G², which unite the ends of the said bows G', as will be understood from Figs. 3 and 5. From this it will be seen that the bows G', 75 cross-pieces G², and sieve G are independent of the rest of the machine and may be removed and put in place at pleasure. Sieve I may also be removed with its slats or bars J'. The said bows are by preference of steel or 80 other spring metal of a size to fit snugly in the channels k. They are simply sprung into the said channels under the lugs k', which hold the sieve, and when so in place the inner sieve is supported and re-enforced by the 85 strong outer sieve I, so that pressure upon the inner sieve cannot bulge it out of shape at any point.

The machine is provided with a cover A', which is to be closed during operation, and 90 it is also provided with a receptacle A² to receive the pulp. The seeds and skins and all foreign matter not forced through the sieves are discharged at the outlet-opening D' in the inner end wall D, and this opening 95 may be closed more or less to regulate the discharge by a door or slide D². (Shown clearly in Figs. 1 and 2.)

Having thus described my invention, what I claim as new, and desire to secure by Letters Patent, is—

In a pulp-machine, the curved ribs K, attached to the main frame and channeled or grooved, as at k, in their upper surfaces and provided with the outer re-enforcing sieve I, in combination with the inner fine sieve G

and bows G', to which the said fine sieve is attached, said bows being adapted to fit in the channels of the curved ribs K, substantially as described.

CHARLES S. BUCKLIN.
